[57] CLAIM

The ornamental design for an elastic projectile for a handgun projector, as shown and described.

DESCRIPTION

FIG. 1 is a top perspective view of an elastic projectile for a handgun projector embodying my new design; FIG. 2 is a top plan view thereof, the bottom being identical with that shown in FIG. 2;

FIG. 3 is a rear elevational view thereof;

FIG. 4 is a side elevational view thereof, the side opposite being identical with that shown in FIG. 4; and

FIG. 5 is a front elevational view thereof.

Fig.1.**Fig. 2.****Fig. 3.****Fig. 4.****Fig. 5.**
